UNITED STATES PATENT OFFICE.

CLARENCE W. MARSH, OF GREENWICH, CONNECTICUT, ASSIGNOR TO HOOKER ELECTROCHEMICAL COMPANY, OF NEW YORK, N. Y., A CORPORATION OF NEW YORK.

ELECTROLYTIC CELL.

1,075,660.

Specification of Letters Patent. Patented Oct. 14, 1913.

Application filed April 18, 1913. Serial No. 762,045.

To all whom it may concern:

Be it known that I, CLARENCE W. MARSH, a citizen of the United States, residing at Greenwich, in the county of Fairfield and State of Connecticut, have invented certain new and useful Improvements in Electrolytic Cells, of which the following is a specification.

This invention relates to electrolytic cells of the diaphragm type intended especially for the decomposition of solutions of the chlorids of sodium and potassium.

A primary object of the invention is the provision of a construction which is applicable to cells having a high ampere capacity, wherein the electrical connections for individual cells as well as for a series of cells are greatly simplified, and the weight of metal necessary for such connections is minimized, and wherein the installation is rendered more flexible both as regards the mode of electrically connecting the units and the capacity of the series-connected units.

For a full understanding of the invention, it will be described by reference to a specific embodiment thereof, as shown in the accompanying drawings, wherein—

Figure 1 represents two multiple-compartment units, that on the right in end elevation, and that on the left in vertical section on line I—I of Fig. 2; Fig. 2 is a partial horizontal section of one of the cells on line II—II of Fig. 1; Fig. 3 is a perspective view of the cathode and diaphragm removed from the cell, one of the cathode pockets being in vertical section; and Fig. 4 is a vertical section on line IV—IV of Fig. 3.

The cell illustrated comprises a concrete cell-body consisting of a bottom 1, top 2, end-walls 3 and two intermediate transverse septa 4, 4, these parts providing three vertically-superposed anode chambers 5, identical in form and size. The cell-body may be integral or constructed in several parts, as desired. Each anode chamber 5 is a long, relatively low chamber, arched upwardly as at 6 to provide space for collection of chlorin and for adjusting the level of the electrolyte to maintain a constant flow through the diaphragm.

7 represents the inlet for fresh electrolyte, and 8 a wash-out opening.

10, 10 represent in dotted lines vertically-

elongated overflow apertures in the end-wall 3, through which the spent electrolyte passes from each anode chamber into an exterior acid-proof casing 11, flowing thence to the main conduit through pipes 12 which are vertically adjustable to control the level of the electrolyte in the several anode chambers. The pipes 12 are of such capacity as readily to convey both the outflowing spent brine and the chlorin gas.

13, 13 are recessed side plates of metal, constituting the cathode chambers of the cells, and are held in place by clamping fingers 14, which pass through slots in the channel-bars 15, and are pressed into engagement with the marginal flanges of the side plates by cams 16.

The cathodes 17 are of sheet steel, closely perforated as at 19. The central or perforated portion of the cathodes is, in the preferred construction, deeply flexed or bent in such manner as to form a large number of recesses or pockets 20 which extend rearwardly into and nearly across the anode chamber 5. These several pockets 20 have perforated vertical walls constituting the cathode proper, but are closed at top and bottom by imperforate metal strips 21, 22, welded thereto. Marginal flanges 27 are formed integral with the strips 21, 22, and are in turn secured by welding or riveting to the marginal flanges of the side plates 13. The strips 21, 22 are overlaid with cement 28 or other insulating material resistant to chlorin. The effect of the foregoing construction is that the side-plates 13 and the cathodes 17 are united into a rigid unitary structure which can be removed from the cell by merely loosening the several clamps 14. The diaphragms 18, usually of asbestos paper, are closely applied to the cathodes 17 on the side thereof adjacent the anodes, and are secured by beads 29 of cement at their upper and lower edges.

The anodes 23 are plates of carbon or Acheson-graphite, the entire number of anodes for one of the anode chambers 5, or any number thereof, being assembled in a cement slab 26 cast around their bases, the spacing of the anode plates being such that when the slab is inserted into position as shown in Figs. 1 and 2, the anode plates will extend into the recesses of the cathode between the pockets 20. Each anode plate is provided with a lead cap 24, and the several

plates constituting a single structure are connected by a copper or aluminium bar 25 serving to distribute the current. The anode plates thus assembled constitute a unitary structure which is readily removable, being secured by clamps 14 of the same character as those retaining the side plates 13.

It will be noted that whereas the pockets 20, which open into the recessed cathode compartments 13, are deep narrow recesses having perforated side walls and imperforate upper and lower walls, the correlated recesses which receive the anodes are in open communication with the anode compartment 5 both at top and bottom, with the result that the chlorin gas liberated at the anodes can pass freely upward to the surface of the electrolyte, and by its upward movement will induce an upward flow of electrolyte through these recesses with a corresponding downward flow through the interspaces between the anode plates at the rear of the cell. This circulation follows the course indicated by the arrows in Fig. 1, and its effect is to insure a supply of strong brine at the regions of most intense electrolytic action, and to prevent to a material degree the accumulation of insoluble impurities upon the diaphragm.

30 The anode plates 23 extend horizontally through the wall of the cell opposite the diaphragm, and are thereby brought into position to be coupled directly with the cathode of the adjacent cell by short coupling members 27. This construction results in a great saving of metal conductors as compared with prior constructions in which the anode connections extend through the top of the cell and the coupling connection must be carried thence downwardly and across to the cathode of the adjacent cell. In case of an installation of cells of large ampere-capacity, this saving of conductors may amount to many thousand dollars.

45 In operating the cell for the production of caustic soda and chlorin, the anode compartments 5 are filled with a saturated solution of brine to the bottom of the overflows 10, and a continuous inflow of brine is maintained through the inlet 7. The cathode compartments 13, as well as the pockets 20, are preferably filled with a hydrocarbon oil for the purpose of securing a more rapid and effective removal of the caustic solution from the cathode, as is now well understood in the art. Upon passage of the current, the caustic-soda solution flows outwardly from the pockets 20 and is continuously withdrawn at 30 from beneath the liquid hydrocarbon, the hydrogen meantime escaping through apertures 9. The chlorin liberated at the surface of the anode plates 23 passes upwardly to the surface of the electrolyte and is withdrawn through pipes 12, together with the impoverished electrolyte. The

rapid upward circulation of the electrolyte through the vertical anode recesses permits the employment of very high current-densities which may be in excess of 100 amperes per square foot of cathode surface; and the short coupling members 27 between adjacent cells permit the resulting heavy current to be handled with economy as regards the weight of metal required. It will be observed that the cell-body in the form illustrated is perfectly symmetrical, with the result that the anode and cathode elements are mutually interchangeable. This renders the structure extremely flexible as regards its mode of connection in the electric circuit. Thus, as illustrated in Fig. 1, the three superposed cells are connected electrically in parallel by the conductors 29, the three cell-compartments thus constituting a single series-unit. This mode of connection involves the advantage that any individual cell-compartment may be disconnected for the purpose of cleaning or repair, the remaining cell-compartments working under a temporary overload, it being therefore unnecessary to disconnect the entire cell. On the other hand, in case it is desired to connect the several superposed compartments electrically in series, to conform to the capacity of the generator or for any other reason, this is very readily accomplished by merely reversing the position of the anode and cathode in the central compartment, when the series connection may be made by short vertical coupling members similar in all respects to the bars 29.

I claim:—

1. In an electrolytic cell of the class described, a cell-body having therein a plurality of superposed chambers for electrolyte, each of said chambers provided with opposite lateral openings for receiving the electrodes.

2. In an electrolytic cell of the class described, a symmetrical cell-body having therein a plurality of superposed chambers for electrolyte, each of said chambers provided with opposite lateral openings for receiving the electrodes, all of said openings being of like form and area, whereby the several electrodes are mutually interchangeable.

3. In an electrolytic cell of the class described, a cell-body having a chamber for electrolyte provided with opposite lateral openings, a previous cathode and diaphragm adapted to cover one of said openings and extending into said chamber at a plurality of points, and a composite anode structure adapted to cover the other of said openings, the individual anodes projecting into said chamber between the cathode extensions.

4. In an electrolytic cell of the class described, a symmetrical cell-body having a chamber for electrolyte provided with oppo-

site lateral openings of like form and area, a perforated cathode and diaphragm adapted to cover one of said openings and extending into said chamber at a plurality of points, and a composite anode structure adapted to cover the other of said openings, the individual anodes projecting into said chamber between the cathode extensions, and said anode and cathode structures being 10 mutually interchangeable.

5. In a cell of the class described, a cell-body having a plurality of superposed chambers for electrolyte, opposite lateral openings for each chamber, a pervious cathode and diaphragm adapted to cover one of the openings of each chamber and extending thereinto at a plurality of points, and a composite anode structure adapted to close the other opening of each said chamber, the individual anodes projecting into said chamber between the cathode extensions.

20. 6. In an electrolytic cell of the class de-

scribed, a symmetrical cell-body having a plurality of superposed chambers for electrolyte, opposite lateral openings for each chamber, all of said openings of like form and area, a pervious cathode and diaphragm adapted to cover one of the openings of each chamber and extending thereinto at a plurality of points, and a composite anode structure adapted to close the other opening of each said chamber, the individual anodes projecting into each chamber between the cathode extensions, and said anode and cathode structures being mutually interchangeable, whereby the superposed units may be directly connected either in series or in parallel.

15. 7. In testimony whereof I affix my signature 25 in presence of two witnesses.

CLARENCE W. MARSH.
